UNITED STATES PATENT OFFICE.

JOHN EPPLER, OF PHILADELPHIA, PENNSYLVANIA.

MACHINE FOR KNITTING LACEWORK.

1,327,228.

Specification of Letters Patent.

Patented Jan. 6, 1920.

Application filed June 13, 1918. Serial No. 239,746.

To all whom it may concern:

Be it known that I, JOHN EPPLER, a citizen of the United States, residing at Philadelphia, county of Philadelphia, and State of Pennsylvania, have invented a new and useful Improvement in Machines for Knitting Lacework, of which the following is a full, clear, and exact description, reference being had to the accompanying drawings, which form a part of this specification.

My invention relates to machines for knitting lacework and especially to that type thereof comprising bars, guiding the weft threads, which are slidable back and forth for variable distances in accordance with the pattern or design of the fabric to be woven. These bars are actuated by monitors, which comprise drums, located toward opposite ends of the machine, which are turnable step by step and are also reciprocable longitudinally toward the ends of the bars and in the direction of their extension, these drums carrying pattern chains provided with removable radial pins which engage the ends of the bars and push them longitudinally a distance dependent upon the length of the pins. In the actual use of these machines, the means for actuating and controlling these bars and monitors has not been satisfactory, and it is the object of my invention to improve these means.

One source of trouble has arisen from the difficulty of removing and replacing the pins and securely holding them in place. There are as many pins on each link of the pattern chain as there are bars to be actuated and there are a large number of links in the chain, so that, in equipping the machine to knit a new pattern, a considerable amount of work is involved in removing and replacing the pins. One part of my improvement involves new means for holding the pins in place in the pockets carried by the links of the pattern chain, whereby they may be effectively secured by simply pushing them into the pockets and may be readily removed by a turning movement followed by withdrawal. These means, however, are not herein claimed, as they form the subject of a separate divisional application filed May 3, 1919, Serial No. 294,503.

Another source of trouble is the maintenance of the bars in the longitudinal position to which they are moved by the pins of the monitor until they are released. It is customary to hold all the bars in position by

means of a single locking contrivance common to all, but perfect alinement between the locking contrivance and all the bars cannot be maintained with certainty and consequently all the bars are not always securely held. I have provided independent locking contrivances for each bar, which are released by the actuation of a common holder for such locks.

The third source of trouble is the liability of the monitor or drum to accidentally turn on its axis in that part of the operation of the machine during which it must be held from turning to insure exact alinement between the pins and the bars actuated thereby. I have provided means which positively and with certainty hold the monitor from turning until it is positively actuated by the intermittent turning mechanism.

A preferred embodiment of the invention is shown in the accompanying drawings, in which—

Figure 1 is a plan view of a part of a knitting machine embodying my invention, many of the parts of the machine not directly co-operating with the novel features thereof being omitted.

Fig. 2 is a detail plan view of part of the pattern chain.

Fig. 3 is a detail side view, partly in section, of one of the links of the pattern chain.

Fig. 4 is a detail perspective view of one of the pins.

Fig. 5 is a perspective view of one end of the machine.

Fig. 6 is an end elevation of the driving shaft and the mechanism actuated thereby for controlling the engagement and disengagement of the locks for the weft bars.

Fig. 7 is a detail view of a part of one of the weft bars and the individual locking contrivance therefor.

Turning in the frame *a* of the machine, toward one end thereof, is the driving shaft *b* which, through a pair of bevel gears *c*, drives a longitudinally extending shaft *d*, which, through a pair of bevel gears *e*, drives a shaft *f*, which extends parallel to the driving shaft *b* and is located toward the other end of the machine. The mechanism at opposite ends of the machine is duplicated so far as concerns the monitor and the means for actuating and locating the same, and a description of one set of mechanism will therefore suffice for both.

Secured to and extending longitudinally from the frame *a* toward one end of the ma-

chine are two pairs of parallel rods *g*, upon which slides a cross head *h* which affords bearings for the drum *i* of the monitor. The drum *i* carries the pattern chain *j*, several links of which are shown in Fig. 2. A take-up roller 25 on a guide-frame 26 projecting longitudinally from the cross head *h* affords means to support the pattern chain, as indicated by dotted lines in Fig. 1. Each link is provided with a series of pockets *k*, shown in Figs. 2 and 3, corresponding in number with the weft bars *m*, which are slideable longitudinally on the frame of the machine in the usual manner. Extending transversely of the axes of the pockets are spring wires *n*, which act as retainers for the pins *p*. I have shown one wire for two adjacent pockets, opposite ends of the wire extending, through slots *t*, in the respective pockets considerably to one side of their axes. Each wire between its ends is bent around a screw *o* located between the pockets and threaded into the body of the link. Each pin *p*, one of which is shown in Fig. 4, has a beveled inner end *r* and a cross notch *s* back of the bevel.

To insert a pin *p* in a pocket *k* the pin is positioned so that its bevel *r* is on the same side of the pocket as the retainer *n*. It is then pushed into the pocket, the retainer being displaced sidewise by the bevel and afterward snapping into the notch *s*. The pin is thus automatically held so securely to the chain that it cannot be accidentally displaced. To remove the pin it is only necessary to first partially rotate it, thereby forcing the retainer *n* outwardly, whereupon the pin may be readily withdrawn.

It will thus be understood that not only are the operations of removal and replacement of pins very simple and expeditious, but no separable fastening devices are required and the pins are held in place with more certainty and security than by the means heretofore employed.

Opposite end hubs of each drum *i* are engaged by the slotted forked ends of a rocking arm *u*, the lower end of which (not shown) is pivoted in the usual manner. The arm *u* is reciprocated by means of a link *v*, one end of which is connected to the arm *u* and the other end of which is connected to a crank *w* on the shaft *f* (or *b*). Thereby the drum *i* and the corresponding cross head *h* are reciprocated on the rods *g*. It will be understood that when the monitor is moved inward a set of pins *p* must be in exact alinement with the bars *m* and that the drum *i* must be positively held from turning and that, upon recession of the monitor, the drum must be turned to exactly the position required to bring the next set of pins *p* into position for operation and must be again locked from turning until after the monitor has advanced and again

receded. The usual means for intermittently turning the drum comprise a ratchet wheel *x* on the shaft of the drum *i* and a pawl *y* adjustably pivoted on the machine frame. It will be understood that as the monitor approaches the end of its outward travel, the pawl *y* is engaged by the ratchet *x*, the latter being thereby turned until the pawl drops back of the next tooth. To prevent the drum turning beyond the position required to bring the next set of pins *p* into proper position, the drum carries a notched wheel *z* which is engaged by a locking pin 10. The means for controlling the operation of this locking pin forms the second of the novel features of the present invention.

This locking pin is carried by a longitudinally extending lever 11, which is pivoted at 12 on an arm 13 secured to the cross head *h*. The lever is always under tension so as to hold the locking pin 10 in engagement with the notched wheel *z* or to cause the pin to snap into engagement therewith when a notch in the wheel is brought into alinement with the pin. The means shown for imposing the desired tension on the lever 11 is a spring 14 connecting the lever with an arm 15 secured to the lever *u*. To prevent the drum *i* from turning too freely, a brake-band 16, secured to the arm 15, engages a part of the periphery of the notched wheel *z* and is connected with the lever 11 by means of a spring 17. It will thus be understood that provision must be made to positively lift the lever 11 and withdraw the locking pin 10 from engagement with the notched wheel *z* just before the engagement of the pawl *y* with ratchet *x*. This is effected by means of the following contrivance.

The free inner end of the lever 11 carries a pin 18 which slides in a slotted guide plate 19 secured to and extending longitudinally from the machine frame. The bottom of the slot is level and during the inward movement of the monitor the pin 18 on the end of lever 11 slides over and upon this level guiding face. In such inward movement, it lifts the free end of a cam-lever 20 pivoted on a bracket 21 secured to the guide-plate 19. The width of the outer part of the slot of the guide-plate is such as to allow sufficient upward displacement of the cam-lever to allow the pin to pass under and lift and clear the cam-lever in the advance movement of the monitor and to leave sufficient space between the cam-lever and the upper face of the slot to allow the pin 18 of lever 11 to pass over it in the return movement of the monitor, thereby lifting the lever 11 on its pivot, withdrawing the locking pin 10 from the notched wheel *z* and allowing the pawl *y* to turn the ratchet wheel *x* and the drum *i*. When the drum *i* has turned into position to bring the next notch of the wheel *z* under the pin 10, which is after the pin 18

has overridden the cam-lever 20, the pin 10 snaps into engagement therewith and so remains until after the monitor has again advanced and has partly completed its return movement. During the last half of the advance movement and the first half of the return movement of the monitor, the lever 11 is held down, not only by the tension mechanism described, but also positively by the confinement of the pin 18 in the narrow part of the slot of guide 19.

While the weft bars *m* are pushed in opposite directions by the pins *p* of the two pattern chains, they are at no time held by either set of pins from moving in one direction or the other and for a large part of the time are not held by the pins from moving in either direction. It is necessary to lock these bars in the precise position to which they are moved by the pins *p* and to unlock them preparatory to their actuation by the pins. To effect this result each bar *m* is provided with a rack 30 which is engaged by a latch. There are as many latches as there are bars, but all the latches are carried by a common vertically reciprocable carrier plate 31. The lower end of the carrier is stepped to correspond with the variation in level of the several bars *m*. Extending vertically and slidably through the carrier plate are the latches, each latch comprising a rack engaging head 32, guided in a recess 34 in the carrier, and a rod 33 extending loosely through, and projecting above the top of, the carrier. Threaded on the projecting upper end of the rod 33 is a nut or nuts 35. Confined with the recess 34, above the head 32 of the latch, is a coil spring 36.

The latch carrier 31 has dovetailed ends slidable in brackets secured to the machine frame. It is moved up and down by means of a curved rocking lever 37, pivoted between its ends on the machine frame and having at one end a pin and slot engagement with the carrier 31 and at its other end having a roller 38 held in operative relation with a cam 39 by means of a spring 40. On the shaft of the cam 39 is a bevel gear 41 which is driven by a bevel gear 42 on a shaft 43. Bevel gears 44, 45 connect the shaft 43 with the driving shaft *b*.

The described parts are so arranged that immediately after the bars *m* have been moved by one set of actuating pins *p* into their predetermined positions, the carrier 31 is dropped sufficiently to cause the several latches 32 to engage the racks 30 of the corresponding bars *m*. The carrier is dropped to the position shown in Fig. 7 so as to insure the descent of the carrier to a level which will with certainty insure the engagement of all the latches. To the extent that the carrier clears the nuts 35 the springs 36 will be compressed and thereby

hold the latches in engagement with the racks. Just prior to the actuation of the bars *m* by the other set of pins *p*, the carrier is lifted, thereby, through the nuts 35, lifting the latches 32 out of engagement with the racks 30.

By thus providing for the limited independent movement of the several latches 32, any slight variation in distance between the several racks 30 and their corresponding latches 32 when the carrier 31 is in raised position, or any slight variation in the depth of the teeth of a rack, will not interfere with the proper and certain operation of the latches when the carrier 31 is depressed.

Having now fully described my invention, what I claim and desire to protect by Letters Patent is:

1. In a machine for knitting lace, the combination with a pattern chain drum and means to reciprocate and intermittently rotate the drum, of a sliding lever reciprocable with the drum, means controlled by the lever to lock the drum from turning, means normally retaining the lever in locking position, and means adapted, in the receding movement of the drum and lever, to actuate the lever to release said holding means.

2. In a machine for knitting lace, the combination with a pattern chain drum and means to reciprocate and intermittently rotate the drum, of a sliding lever reciprocable with the drum, means controlled by the lever to lock the drum from turning, and a cam adapted, in the receding movement of the drum and lever, to shift the lever and release the drum-locking means.

3. In a machine for knitting lace, the combination with a pattern chain drum and means to reciprocate and intermittently rotate the drum, of a sliding lever reciprocable with the drum, means controlled by the lever to lock the drum from turning, and a movable cam adapted, in the forward movement of the drum and lever, to be displaced out of the path of movement of the lever and in the receding movement of the drum and lever to shift the lever and release the drum-locking means.

4. In a machine for knitting lace, the combination with a pattern chain drum and means to reciprocate and intermittently rotate the drum, of a sliding and swinging lever reciprocable with the drum, means controlled by the lever to lock the drum from turning, a guide plate having a surface along which the lever is guided in its forward sliding movement, and a swinging cam interposed in the path of travel of the lever and overhanging said surface and adapted, in the forward sliding movement of the lever, to be engaged thereby and lifted, and adapted, in the return sliding movement of the lever, to swing said lever into position to release the drum-locking means.

5. In a machine for knitting lace, the combination with a pattern chain drum and means to reciprocate and intermittently rotate the drum, of a sliding and swinging lever reciprocable with the drum, means controlled by the lever to lock the drum from turning, a guide plate extending in the direction of reciprocation of the lever and provided with a slot having a flat lower 5 face and relatively narrow at its inner end and relatively wide at its outer end, and a cam located in the wider outer end of the slot, said cam being pivoted at its outer end, its inner free end extending inwardly and 10 downwardly toward the level lower face of the slot, said cam being displaceable upwardly by said lever in its forward movement and operating, in the return movement of the lever, to swing the lever upwardly and thereby release the drum-locking means.
- 10 6. In a machine for knitting lace, the combination with a pattern chain drum and means to reciprocate and intermittently rotate the drum, of a notched wheel turning 15 with the drum, a lever pivoted at its outer end and reciprocable with the drum, a locking pin carried by the lever and adapted to engage the notched wheel, tension means acting upon the lever to cause the locking 20 pin carried thereby to engage the notched wheel and remain in engagement therewith until the lever is positively moved into position to disengage the pin from the wheel, and a swinging cam adapted in the 25 forward movement of the lever, to be engaged and displaced thereby and in the rearward movement of the lever, to engage the lever and swing it into position to disengage the pin from the wheel.
- 30 7. In a machine for knitting lace, the combination with longitudinally shiftable weft-bars, of locking contrivances for the respective bars, common means to move all said locking devices into and out of operative position, said means, in its movement to lock, having a limited movement beyond said locking devices, and springs, compressible in such movement, operating to hold the latches in engagement with the rack-bars.
- 35 8. In a machine for knitting lace, the combination with longitudinally shiftable weft-bars, of a carrier, separate locking devices on the carrier, one for each bar, movable relatively to the carrier, springs, one for 40 each locking device, adapted to hold the locking devices in locking engagement with the respective bars when the carrier is in appropriate position, and means to move the carrier to bring the locking devices into and 45 out of operative relation with the respective bars.
- 45 9. In a machine for knitting lace, the combination with longitudinally shiftable weft-bars and racks on the bars, of a carrier and 50 means to reciprocate the carrier toward and

from the racks, latches, one for each bar, movable on the carrier and independently of each other, and springs operating upon the latches to insure their proper locking engagement with the respective racks notwithstanding variations in distance between the several racks and their corresponding latches or slight variations in the depth of the rack teeth.

55 10. In a machine for knitting lace, the combination with longitudinally shiftable weft-bars and racks on the bars, of a carrier and means to reciprocate the carrier toward and from the racks, latches having locking heads adapted to engage the racks and slideable in recesses in the carrier and having shanks also slideable in the carrier, means whereby, as the carrier is raised, it engages the latches and withdraws them from locking engagement with the respective racks, 60 and a spring confined in each recess between the locking head of the latch and the base of the recess whereby, as the carrier approaches the racks, the several latches will engage the respective racks before the completion of the carrier's movement, causing the springs, as the carrier completes its movement, to be compressed against the locking heads of the latches.

65 11. In a machine for knitting lace, the combination with longitudinally shiftable weft-bars, of a carrier movable toward and from the weft-bars, and locking contrivances for the several bars independently retractable relatively to the carrier in the movement of the carrier toward locking position.

70 12. In a machine for knitting lace, the combination with longitudinally shiftable weft-bars, of locking contrivances for the several bars, independent springs engaging the respective locking devices, and common positively actuated means adapted to release the locking contrivances from engagement with the weft-bars and adapted to coöperate with the springs to effect locking engagement of the locking contrivances with the weft-bars.

75 13. In a machine for knitting lace, the combination with longitudinally shiftable weft-bars, of a carrier movable toward and from the weft-bars, locking contrivances for the several bars independently retractable relatively to the carrier in the movement of the carrier toward locking position, and springs compressible, in the relative retraction of the locking devices, after the engagement of the corresponding locking devices with the weft-bars.

80 In testimony of which invention I have hereunto set my hand, at Philadelphia, Pa., 125 on this 23rd day of May, 1918.

JOHN EPPLER.
